Inventor

Charles Dietz
By Raymond & Aspinwall, Atty's

UNITED STATES PATENT OFFICE.

CHARLES DIETZ, OF CHICAGO, ILLINOIS.

DOOR-HINGE.

SPECIFICATION forming part of Letters Patent No. 609,878, dated August 30, 1898.

Application filed February 28, 1898. Serial No. 672,038. (No model.)

To all whom it may concern:

Be it known that I, CHARLES DIETZ, a citizen of the United States, residing at Chicago, in the county of Cook and State of Illinois, 5 have invented certain new and useful Improvements in Hinges, of which the following is a full, clear, and exact description, reference being had to the accompanying drawings, forming part of this specification.

10 My invention relates to certain new and useful improvements in hinges, and particularly of that type designed for use on double-swing doors.

15 The object of this invention is to provide a door-hinge for double-swing doors constructed and adapted to operate in such a manner that when the door has been opened and released it is free to swing back into its normal closed position and will assume that position 20 immediately without swinging back and forth for some time, as is now customary with the ordinary double-swing doors.

25 Another object of the invention is to provide hinges for a swing-door of such a character that the pressure required to open the door need not be increased as the door is opened, but always remains substantially the same.

30 Another object of the invention is to provide a door-hinge constructed in such a manner that the door is lifted as it is swung open and slides down to its normal position, at which time the door has reached the lowest limit of its movement and is closed.

35 Another object of the invention is to provide a hinge for double-swing doors which locks the door to the door-frame, so that it cannot be removed while the hinge is fastened in place, but at the same time permits 40 the free movement or swing of the door.

Another object of the invention is to provide a door-hinge which constitutes a locking device to secure the door to the frame when the door is opened as well as when it is closed.

45 My invention also has in view other important objects, which will be pointed out hereinafter in the detailed description thereof.

In the drawings, Figure 1 is an elevation, partly in section, showing my improved door-hinge applied to a door. Fig. 2 is a similar view with the door open. Fig. 3 is a perspective view of a door-frame, also showing the

door open. Fig. 4 is a sectional view on the line 4-4 of Fig. 2. Fig. 5 is a similar view showing the hinge constructed to swing the 55 door in one way only.

Referring to the drawings, in which like letters of reference denote corresponding parts in all the figures, A designates a door-frame, and B a door; it being understood that my invention is applicable to doors and door-frames of any known description. In some cases I have found it necessary, as shown in the drawings, to bevel the back edge of the door, as shown at a, and the upper edge, as shown at 60 a', and also cut out the upper corner b of the door and secure it in the corresponding corner of the frame, because the construction of the hinge is such that the door is given an upward movement coincident with its swinging 65 movement and the upper edge of the door and the corner thereof must be formed in such a manner that the door in its upward movement will clear the frame.

70 My invention is particularly adaptable to 75 double swing-doors, and for this reason I will now describe the construction, arrangement, and operation of a hinge of this character. The hinge comprises two parts or castings, which may be termed "male" or "female," 80 one part C being provided with twin pintles c, adapted to fit and operate in corresponding sockets c' in the other part D. The pintles are substantially circular in cross-section and adapted to fit snugly in the sockets c', 85 these sockets being open on one side, so that the pintles may slip in and out freely. The walls of the sockets at the upper and lower ends are extended inward to form retaining-guides d, and as the distance between these 90 guides is less than the distance between the outer ends of the circular pintles the lower ends of said pintles are cut out and squared on their outer sides, as indicated at d', to permit the lower retaining-guide d to slip off of 95 the pintles. As the door is swung one socket slips off of its pintle, while at the same time the other socket slips around its pintle to take a permanent hold thereon, and for this reason also it is important that the walls of 100 the lower part of the sockets should be continued in the form of retaining-guides and the outer sides of the lower ends of the pintles should be cut away, so that while the

5 sockets can be swung outwardly away from the pintles when the door is in its normal position at right angles to the frame immediately after the door is swung to one side or the other the retaining-guide will slip from its position in alinement with the outer side of the lower end of the pintle and take hold thereof to hold the door rigidly in place on the pintle. The fixed or casing member C of 10 the hinge comprises a back plate E, through which the screws pass, securing this portion to the door-frame, and forwardly-projecting arms e, which carry the pintles. The female portion of the hinge is provided with a hood 15 F at the top, the sockets c' to receive the pintles, and the socket f on its opposite side and between the pintle-sockets to receive the door.

The arms *e* are provided with cam-faces *G*, and inclined slots *g* are provided in the socket-plate or female portion of the hinge *D*, these slots being adapted to receive the cams *G* when the door is swung from side to side. These slots are inclined downwardly, and the upper inclined wall of each slot is the operative portion thereof and rides on its corresponding cam *G* when the door is swung, thereby raising the door, and when the pressure on the door is released its weight will cause it to swing backward into its normal position, the upper inclined edge of the slot riding down over the cam *G* accelerating the movement of the door and also bringing it to

lowest limit of its movement instead of allowing the door to swing back and forth. It is obvious, therefore, that the slots in the socket-plate may be of a different character than that shown, as it is only essential to provide inclined edges on the socket-plate to ride on the cams G.

40 ride on the cams G. The assembled door parts and supporting the door in place the pintle-plates are secured in their proper position in the door-frame, and the socket-plates are then arranged on the door-frame, the socket-plates being arranged and adjusted in the manner which will permit of their being properly hung on the pintles, and the door being fastened thereto in an open position and the door fastened thereto, and into the edge of the door, which is an awning to one side, the retaining guide or swivel being attached to the door, and the door being adjusted to the correct position, so the pintle-plate is properly secured to the door, the pintle beyond the cut-out portion and secures the door from becoming displaced and 60 holds it in its proper vertical position. The inclined wall of the slot g rides up over its cam G and lifts the door, which is thus swung outward away from the door-frame and lifted upward coincidentally with its swinging movement. The upper edge of the door being beveled and the corner being cut out in the manner heretofore described permits of

the door being lifted without binding against the frame, and the pressure required to open the door does not increase as the door opens, as is customary with spring-hinges, but always remains the same in degree from the beginning of the swinging movement until the door reaches the outward limit of its swing.

When the door is opened, it will of course have been lifted to the limit of its upward movement, and the sockets are therefore open at their bottom to receive the lower end of the pintles, which may pass therethrough. When the door is opened in this manner, it is secured against displacement by the engagement of the inclined walls of the slot in the socket-plate with the arm on the pintle-plate and the engagement of the pintle in the lower portion of the socket with the retaining-guide and the other walls of the socket. The distance between the cut-out sides of the pintle is sufficiently less than the distance between the retaining-guides of the sockets to permit one guide to swing free of its pintle and without catching or engaging the same, while the other guide immediately engages and takes hold of its pintle. The lower ends of the pintles do not necessarily assist in holding the door in place when the door is in its normal position; but immediately the door is swung to one side the lower end of the pintle on that side is engaged by the lower walls of the socket in such a way as to hold

When the door is in its normal position, the upper ends of the pintles are located within the hooded upper ends of the sockets, and the door is thereby prevented from displacement.

It will be observed by those skilled in the art that in my hinge is divided centrally and longitudinally into two half-things, each of which admits a hinge for a door swinging in one direction as shown in Fig. 5. I do not consider it necessary to enter into a detailed description of the hinge, as it is a hinge of this construction, it will be exactly the same in construction and operation as the hinge of the double-swing hinge shown in my application for a patent.

b hinge heretofore described. In the form and proportion of parts and details of construction departing from the spirit or sacrificing the right to claim all such changes as fairly and naturally resulting therefrom.

Having thus fully described my invention, I wish to have it secured by Letters Patent, is

1. In a door-hinge, the combination with a plate having a socket therein, the wall of which is extended to form a retaining-guide, of a pintle for said socket having its lower end cut out on one side, substantially as and for the purpose described. 130

for the purpose described.

2. In a door-hinge, the combination with a cam and a pintle having its lower end cut out

on one side, of a socket-plate having its socket-wall extended to form a guide, said plate having an inclined slot therein, the upper wall of said slot being constructed to ride on the 5 cam of the pintle, substantially as described.

3. In a door-hinge, the combination with twin pintles having cams thereon, of a plate provided with sockets to receive the pintles and having inclined walls thereon to ride on 10 the cams to lift the door when it is swung, substantially as described.

4. In a door-hinge, the combination with twin pintles having their lower ends cut out 15 on their outer sides, of a plate provided with sockets to receive the pintles and retaining-guides normally clearing the cut-out ends of

the pintles, substantially as and for the purpose described.

5. In a door-hinge, the combination with twin pintles having their lower ends cut out 20 on one side, and cams, of a plate provided with sockets to receive the pintles and having slots therein to receive the cams, the upper walls of the slots being adapted to ride on the cams to lift the door when it is swung and 25 retaining-guides normally clearing the cut-out ends of the pintles, substantially as and for the purpose described.

CHARLES DIETZ.
